(57) **CLAIM**

The ornamental design for a chair and table set, as shown and described.

DESCRIPTION

FIG. 1 is a perspective view of a first embodiment of a chair and table set showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a perspective view of a second embodiment of a chair and table set showing my new design;

FIG. 8 is a front elevational view thereof;

FIG. 9 is a rear elevational view thereof;

FIG. 10 is a left side elevational view thereof;

FIG. 11 is a right side elevational view thereof; and,

FIG. 12 is a top plan view thereof.

The broken lines in the figures are for the purpose of illustrating portions of the chair and table set, which form no part of the claimed design.

1 Claim, 12 Drawing Sheets(56)
